TOY SCALE

Edward Francis Donovan, Dayton, Ohio, assignor
to Cappel, MacDonald and Company, Dayton,
Ohio

Application May 4, 1942, Serial No. 441,695

7 Claims. (Cl. 35—24)

This invention relates to a toy weight scales. An object of this invention is to provide a toy scales which will not only provide amusement or entertainment but also instruction to children.

Another object of this invention is to provide a toy scales of this kind which may be made entirely out of wood and which may be put together or taken apart by a child.

A further object of this invention is to provide a toy scales of this kind which is simple in construction so that it can be sturdily made at a small cost and will withstand fairly rough handling.

A further object of this invention is to provide a toy scales of this kind which can be made attractive by coloring or painting and which embodies a balancing beam or platform formed with sockets to receive weights or blocks which when properly placed will maintain the beam in a horizontal balanced position.

To the foregoing objects and to others which may hereinafter appear, the invention consists of the novel construction, combination and arrangement of parts as will be more specifically referred to and illustrated in the accompanying drawings, wherein is shown an embodiment of this invention, but it is to be understood that changes, variations and modifications may be resorted to which fall within the scope of the invention as claimed.

In the drawings:

Figure 1 is a top plan of a toy scales constructed according to an embodiment of this invention,

Figure 2 is a detail side elevation of the device partly broken away and in section,

Figure 3 is a longitudinal section taken on the line 3—3 of Figure 1,

Figure 4 is a transverse section taken on the line 4—4 of Figure 3,

Figure 5 is a perspective view of one of the platform standards, and

Figure 6 is a perspective view of the base.

Referring to the drawings, the numeral 10 designates generally a base plate which is adapted to be constructed out of wood and in the present instance is rectangular in plan and is provided with beveled side portions 11 and beveled front and rear edge portions 12. The base 10 has formed in the upper side thereof adjacent the opposite sides thereof sockets 13 in which are received the lower ends of dowels 14 carried by upright standards or platform supporting members 17.

There are two of these standards or platform

supporting members 17 which are disposed in confronting position and each standard 17 includes a rectangular body 18 formed at the lower portion thereof with a downwardly extending extension 19 which terminates at the lower ends thereof in feet 15 and 16. Each standard 17 at the upper end portion thereof is formed with a bearing 20 which is connected with the body 18 by means of a connecting member 21. The bearing 20 is formed on the inner side thereof, as shown in Figure 5, with a socket 22 within which a trunnion 23 carried by a platform generally designated as 24 is adapted to rockably engage. The platform 24 comprises an elongated rectangular body 25 which has secured to or formed integral therewith in the transverse median an upstanding lug or block 26 within which the oppositely extending trunnions 23 are adapted to be secured in any suitable manner.

The trunnions 23 may be constructed in the form of dowels which are secured as by gluing or the like within the block 26 and the trunnions 23 extend laterally from the opposite end portions of the block 26 for rockable engagement within the sockets 22. The platform 24 on the upper side thereof has formed therein a plurality of sockets or recesses 27, 28 and 29 disposed in longitudinally spaced apart relation and extending from one side of the block 26.

The platform 24 also has formed on the opposite side of the block 26 sockets 30, 31 and 32. A weight member 33 which is of generally cylindrical configuration is adapted to engage in any one of the sockets formed in the platform 24 and the weight 33 at its upper end is formed with a rounded end portion 34, whereas the lower end of the weight member 33 is squared off as at 35 so that the weight 33 will removably engage in the selected socket and stand in upright position with respect to the upper side of the platform 24. A second weight member 36 is constructed similar in every detail to the weight member 33, but is substantially longer than the weight member 33. A third weight member 37 which is similar to the two weight members 33 and 36 is adapted to engage in another one of the sockets of the platform 24 and the weight member 37 is longer than the weight member 36. There are two sets of the weight members 33, 36 and 37 which may be positioned in selected sockets of the platform 24 so that the platform or beam 24 will be disposed in balanced or horizontal position.

The weight members are here shown as being disposed with the shortest one innermost and the

longest one outermost, but it is to be understood that the weight members may be disposed in any other suitable order.

It is to be understood that the invention is not limited to the exact construction shown, but may be otherwise modified without departing from the spirit or scope of the invention as defined in the claims.

intermediate length weight member 36 next to the short weight member 33 and the long weight member 37 disposed in one of the outermost sockets. However, it will be apparent that the arrangement of the weight members may be varied in any manner desired, and unless the weight members on one side of the block 26 are equal in weight to the weight members on the opposite side of the block 26, the platform or beam 24 will not balance.

With a weighing scale as hereinbefore described, a child may use the scales as an educational device or as a means of amusement and due to the fact that the entire device is constructed out of wood, the device may be easily and cheaply manufactured so that it may be sold at small cost. Furthermore, due to the rugged construction of the device, it will not readily get out of order or become broken. If desired, the entire device may be made as a put-together structure which may be assembled by a child, in which case, the dowels 14 may frictionally engage in the sockets or recesses 13. However, if desired, the dowels 14 may be glued or otherwise fixedly secured in the sockets 13 so that the device will be maintained in assembled condition.

What I claim is:

1. A toy scales comprising a base, a pair of upstanding standards rising from the base, a weighing platform, means rockably mounting said platform on said standards, said platform formed with at least two series of weight receiving sockets in the upper side thereof and extending respectively outwardly from the fulcrum thereof, and weight members selectively engageable in said sockets.

2. A toy scales comprising a base formed with recesses in the upper side thereof, a pair of upstanding standards each having a recess in the lower end thereof, dowels engaging in the recesses of said base and said standard to hold said parts together, an elongated weighing platform, means rockably mounting said platform on said standards, said platform formed with longitudinally spaced apart recesses in the upper side thereof, and weight members selectively engageable in said latter recesses.

3. A toy scales comprising a base formed with recesses in the upper side thereof, a pair of upstanding standards each having a recess in the lower end thereof, dowels engaging in the recesses of said base and said standards to hold

said parts together, said standards having confronting bearing sockets, a weighing platform, trunnions carried by said platform engaging in said sockets, and weight members, said platform having longitudinally disposed means for receiving said members.

4. A toy scales comprising a weighing platform, an upstanding block extending transversely of the upper side of said platform, supporting means for said platform, said supporting means and said block including correlated means rockably mounting said platform directly on said supporting means, and a plurality of weight members, said platform having longitudinally disposed means whereby said weight members may be selectively mounted on said platform at selected longitudinal distances outwardly of said block.

5. A toy scales comprising a weighing platform, an upstanding block extending transversely of the upper side of said platform, supporting means for said platform, oppositely extending trunnions carried by said block, said supporting means having bearing recesses to rockably receive said trunnions, and a plurality of weight members, said platform having longitudinally spaced apart sockets means whereby said weight members may be mounted on said platform at selected distances outwardly of said block.

6. A knocked down weight scales structure comprising a base, a pair of supports removably mounted thereon, a balance beam directly rockably mounted on said supports, said balance beam having a series of longitudinally spaced apart sockets in the upper surface thereof, and a series of blocks adapted to be seated in said sockets.

7. In a device of the kind described a base having a pair of sockets in the top thereof, a pair of supports each having a socket in the lower or bottom portion thereof to receive a dowel pin, the other end of said dowel pin adapted to fit within the socket in said base to thereby hold the support in upright position on said base, a weighing platform rockably mounted on said supports by means of trunnions fitted within said pair of top sockets and a series of weights engageable with said platform, said platform having means disposed longitudinally thereof for holding said weights.

EDWARD F. DONOVAN.
